UNITED STATES PATENT OFFICE

162,928

WARNING SIGNAL

Dempsey C. Britton, Cold Springs, Ky.

Application August 24, 1950, Serial No. 11,922

Term of patent 14 years

(Cl. D72—1)

To all whom it may concern:

Be it known that I, Dempsey C. Britton, a citizen of the United States and a resident of Cold Springs, State of Kentucky, have invented a new, original, and ornamental Design for a Warning Signal, of which the following is a specification, reference being had to the accompanying drawings, forming part thereof, wherein:

Fig. 1 is a side elevation of a warning sign disclosing my novel design;

Fig. 2 is an end view thereof.

I claim:

The ornamental design for a warning signal, as shown.

DEMPSEY C. BRITTON.
